US00D815619S

(12) **United States Design Patent** (10) **Patent No.:** **US D815,619 S**
(45) **Date of Patent:** **** Apr. 17, 2018**

(54) **ELECTRONIC HOUSING**

(71) Applicant: **Peripherii Inc.**, Chappaqua, NY (US)

(72) Inventors: **Priti Moudgill**, Chappaqua, NY (US);
Sonal Budhiraja, Palo Alto, CA (US)

(73) Assignee: **A. JAFFE, INC.**, New York, NY (US)

(**) Term: **15 Years**

(21) Appl. No.: **29/633,217**

(22) Filed: **Jan. 12, 2018**

(57) **CLAIM**

The ornamental design for an electronic housing, as shown
and described.

DESCRIPTION

FIG. 1 is a front top perspective view of the invention.

FIG. 2 is a top plan view thereof.

FIG. 3 is a rear plan view thereof.

FIG. 4 is a left side elevation view thereof.

FIG. 5 is a right side elevation view thereof.

FIG. 6 is a front elevation view thereof.

FIG. 7 is a rear elevation view thereof; and,

FIG. 8 is a front rear perspective view thereof.

The product is an electronic housing for wireless communication elements. No claim is made to the portions of the drawing shown in dash-dash lines. The dash-dot-dot-dash line indicate a claim boundary region. No claim is made to portions which are not shown.

1 Claim, 6 Drawing Sheets
